COLLAPSIBLE WINDER SHAFT

William H. Lieber, Wauwatosa, Wis., assignor to
 D. J. Murray Manufacturing Co., Wausau, Wis.,
 a corporation of Wisconsin

Application November 28, 1938, Serial No. 242,737

2 Claims. (Cl. 242—72)

This invention relates to improvements in the construction and operation of winder shafts for producing rolls of paper, and relates more specifically to an improved collapsible winder shaft assemblage adapted to be readily removed from the paper rolls formed thereon.

Generally defined, an object of the present invention is to provide a new and useful collapsible winder shaft assemblage which is extremely simple and durable in construction and which is moreover highly effective in use.

It has long been common practice in the paper industry, to utilize so-called winder shafts for facilitating the production of rolls of paper of various dimensions. In order to permit ready removal of these shafts after the paper has been rolled tightly thereabout, the shafts are ordinarily formed of two approximately semi-circular sections interconnected by a series of parallel disks or links, the opposite ends of which are connected by pivot pins to the respective sections. By relatively longitudinally shifting the two sections of such a shaft against the expanding action of a spring, the sections may be brought toward each other or collapsed due to tilting of the connecting links, thereby diminishing the shaft diameter and thus permitting free withdrawal of the shaft axially from within the roll of paper. When the collapsing force is released, the spring automatically expands the shaft to its maximum diameter ready for reception of a subsequent roll of paper, by causing the connecting links to again assume positions normal to the longitudinal shaft axis, and in some cases special stops have been provided in order to prevent undesirable overthrow of the links.

Because of the fact that the pressure to which such shafts are subjected during rolling of the paper thereon, is enormous, the relatively frail link pivot pins which must necessarily be used because of limited available space, tend to bend and thereby prevent free collapse and expansion of the shafts. In order to relieve these pins of this abnormal pressure, it has heretofore been proposed to snugly confine the opposite ends of the links in alined grooves or pockets formed in the relatively movable shaft sections, and to provide semi-circular ends for the links, generated about the respective pin axes and having rolling line contact with the bottoms of the respective pockets. With this proposed structure, the links have direct line contact at their opposite extreme ends with the two otherwise separated shaft sections, and thus form struts

which by virtue of these line contacts are intended to relieve the pivot pins of bending pressures. When such an assemblage is new and properly constructed, the struts will probably function as contemplated, but due to repeated collapse and expansion of the shaft, and also due to the high pressure applied at the lines of contact, the link ends will eventually wear and will become distorted so that the pivot pins are no longer protected against lateral pressures tending to bend the same. The proposed assemblage must also be very carefully and accurately constructed so as to function properly, and special stops functioning independently of the links must be provided in order to prevent overthrow of the latter.

The present invention therefore contemplates provision of a simplified and improved winder shaft assemblage wherein the connecting links are converted into direct struts interposed between the expanded shaft sections, without necessity of utilizing rolling contact between the links and shaft sections, thus eliminating necessity of extreme accuracy and care in construction and assemblage and also avoiding excessive wear on parts.

In accordance with the present improvement, each link is automatically converted into a strut having extensive surface instead of merely line contact at the link ends, when the shaft is expanded; and the surfaces of engagement also serve as effective stops for preventing overthrow of the links and thus eliminate necessity of providing special stops. The struts of the present improvement contact the bottoms of the link confining grooves or pockets only when the shaft is fully expanded, and are freely swingable about their pivot pins when the shaft is being collapsed or expanded without engaging the groove bottoms.

A clear conception of an embodiment of the present invention, and of the mode of constructing and of utilizing collapsible winder shafts built in accordance with the improvement, may be had by referring to the drawing accompanying and forming a part of this specification wherein like reference characters designate the same or similar parts in the various views.

Fig. 1 is a part sectional side view of one of the collapsible winder shafts showing the same fully expanded but with the manipulating lever in place;

Fig. 2 is a similar view of the winder shaft of Fig. 1, but showing the assemblage collapsed with the aid of the manipulating lever;

Fig. 3 is a fragmentary enlarged central longitudinal section through the improved winder shaft in expanded condition, and showing several of the improved strut links;

Fig. 4 is a similar fragmentary sectional view showing the shaft sections and link assemblage in collapsed condition; and

Fig. 5 is a transverse vertical section through the expanded shaft, taken along the line 5—5 10 of Fig. 3.

Although the invention has been shown and described herein as being especially applicable to paper roll winder shafts, it is not the intention to thereby unnecessarily restrict the scope 15 and utility of the improvement.

Referring to the drawing, the improved winder shaft assemblage specifically illustrated therein, comprises in general two complementary approximately semi-cylindrical shaft sections 6, 7; 20 a series of similar links 8 each having its opposite ends swingably connected to the shaft sections 6, 7 by means of pivot pins 9, 10 respectively; and a compression spring 11 coacting with spaced lugs 12, 13 formed on the shaft sections 25 6, 7 respectively and tending at all times to expand the shaft to its maximum diameter.

The shaft sections 6, 7 are preferably formed of a solid metal bar rather than of tubing, and the main section 6 is provided with the usual 30 end journal portions 14 which are of lesser diameter than the medial portion of the shaft.

The auxiliary shaft section 7 is disposed within a lateral recess in the main section 6, and both sections 6, 7 have aligned longitudinal grooves 15 35 preferably milled therein, and in which the links 8 are snugly confined but freely swingable. The pivot pins 9, 10 extend across these grooves 15 and are fastened to the respective shaft sections 6, 7 at the opposite sides of the grooves; and the medial groove portion 16 within which the compression spring 11 is confined, may be somewhat 40 enlarged to confine the spring without interfering with its free operation. The two shaft sections 6, 7 are also provided with aligned transverse openings 17, 18 respectively adapted for reception of 45 a shaft collapsing lever 19 as shown in Figs. 1 and 2, but this lever 19 is normally removed from the shaft assembly when paper is being rolled thereon.

Each of the improved connecting links 8 which 50 are confined within the aligned grooves 15 by the pivot pins 9, 10, is of special formation as shown in detail in Figs. 3, 4 and 5. Each link 8 has opposite parallel end surfaces 20 which are adapted 55 to coat with the plane parallel bottoms 21 of the corresponding grooves 15 when the sections 6, 7 are separated or expanded to the maximum extent as in Figs. 1, 3 and 5; but the diagonally opposite portions 22 of each link 8 are cut away at 60 an angle so as to remove the link ends from contact with the groove bottoms 21 and to retain said ends out of contact with these bottoms, except when the shaft is fully expanded. The structure of the links 8 and the location of the pivot pins 65 9, 10 is obviously such that when the links approach parallel positions perpendicular to the longitudinal axis of the split shaft, the end surfaces 20 engage the groove bottoms 21 throughout the entire areas of the surfaces 20 and thus 70 relieve the pivot pins 9, 10 from lateral pressure due to rolling of the paper about the winder shaft; but when the shaft is collapsed, the surfaces 20 immediately disengage the bottoms 21 and the cut-away portions 22 prevent subsequent engagement between the link ends and the groove 75

bottoms while the shaft sections 6, 7 are being displaced relative to each other, or while the shaft is collapsed. Besides providing thrust surfaces at the ends of the links 8, the plane surfaces 20 also serve as stops for preventing overthrow of 5 the links 8 beyond normal, due to the action of the spring 11 which constantly tends to expand the winder shaft.

While the normal operation of the present improved winder shaft assemblage should be clearly 10 apparent from the foregoing detailed description, this operation will again be briefly described. When the shaft has been fully expanded as illustrated in Fig. 1, and the handle or lever 19 has been removed from the openings 17, 18, paper 15 may be rolled about the shaft assemblage in the usual manner. The end surfaces 20 of the several links are then in contact with the plane bottoms 21 of the grooves 15, so that the links 8 provide 20 struts which directly assume the external pressures tending to collapse the shaft, without subjecting the pivot pins 9, 10 to these pressures. The spring 11 which constantly tends to expand the shaft, and thereby also tends to move the links 25 8 perpendicular to the shaft axis, cooperates with 20 the abutment surfaces 20 and with the groove bottoms to form automatic stops for preventing overthrow of the links, so that no additional or special stops are necessary.

After a roll of paper has been wound upon the 30 shaft, and if it becomes desirable to remove the same, the manipulating lever 19 may be inserted within the openings 17, 18 and swung to the position shown in Fig. 2. The links 8 will then be 35 tilted against the action of the spring 11, and the shaft section 7 will be brought toward and into direct engagement with the section 6, thereby collapsing the assemblage and diminishing the external shaft diameter. The lever 19 may then be utilized to withdraw the winder shaft from 40 within the roll of paper, and after such withdrawal the lever may be removed and the shaft permitted to expand preparatory to reception of 45 another roll of paper. During such collapse and expansion of the shaft assemblage, the links 8 are 50 freely swingable about the transverse pivot pins 9, 10, and are guided in the confining grooves 15 of the sections 6, 7.

From the foregoing detailed description it will 55 be apparent that the present invention provides an extremely simple and durable winder shaft assemblage which is highly effective in use and may be readily manipulated to collapse and remove the same from a roll of paper. The improved links 8 are of like construction and are 60 therefore interchangeable, and need not be machined with extreme accuracy except as to distance between the end surfaces 20. The structure requires no special stops other than the surfaces 20 for preventing undesirable overthrow of 65 the links 8, and the links 8 may be readily inserted and removed and have their pivot pins 9, 10 well protected against excessive pressures at all times. The surface contact afforded by the link surfaces 20 and the groove bottoms 21, eliminates possible 70 wear such as is apt to result from the prior line rolling contact, and the improved assemblage has proven highly practical in actual operation. While a spring 11 of the helical compression type 75 has been specifically shown, this spring may obviously be replaced by any other type of spring or other means tending to separate the shaft sections.

It should be understood that it is not desired 80 to limit the invention to the exact details of con- 85

struction or to the precise mode of operation, herein shown and described, for various modifications within the scope of the claims may occur to persons skilled in the art.

5 I claim:

1. A winder shaft comprising, a pair of elongated approximately half-shaft sections having parallel grooves facing each other and provided with parallel bottom surfaces and aligned corresponding side surfaces, a series of parallel links each having its opposite ends disposed within said parallel grooves and each being provided with flat end and side surfaces the latter of which constantly engage said groove side surfaces and the former of which contact the adjacent groove bottom surfaces only when said links are disposed perpendicular to the longitudinal shaft axis, and a pivot pin swingably connecting each end of each link with the adjacent shaft section at the opposite sides of the corresponding groove, said pins and said links being disposed and formed to cause said link end surfaces to move out of contact with said groove bottom surfaces when said shaft sections are moved toward each other and to maintain surface contact with said groove bottom surfaces only when said links are in said perpendicular position.
2. A winder shaft comprising, a pair of elongated approximately half-shaft sections having parallel grooves facing each other and provided with parallel bottom plane surfaces and aligned corresponding plane side surfaces, a series of parallel rectangular links each having its opposite ends disposed within said parallel grooves and each being provided with plane end and side surfaces the latter of which constantly engage said groove side surfaces and the former of which contact the adjacent groove bottom surfaces only when the links are disposed perpendicular to the longitudinal shaft axis, and a pivot pin swingably connecting each end of each link with the adjacent shaft section at the opposite sides of the corresponding groove and remote from the groove bottom, each of said links having its diagonally opposite corners removed and said pivot pins being disposed to cause said link end surfaces to move out of contact with said groove bottom when said shaft sections are moved toward each other and to maintain surface contact with the groove bottom surfaces and relieve said pins from lateral pressure tending to move the shaft sections together only when said links are in said perpendicular position.
